UNITED STATES PATENT OFFICE

2,565,925

METHOD OF MANUFACTURING GUIDE
VANES FOR AXIAL FLOW TURBINES
AND COMPRESSORS

Adrian Albert Lombard, Clitheroe, and Walter Edward Dazeley, Twiston, near Clitheroe, England, assignors to Rolls-Royce Limited, Derby, England, a British company

Application March 24, 1947, Serial No. 736,806
In Great Britain April 10, 1946

2 Claims. (Cl. 90—11)

1

This invention relates to the manufacture of guide vanes for axial-flow turbines and compressors. The throat area of the nozzle guide vanes (that is the area between the trailing edge of each vane and the adjacent vane on its concave side) of an internal combustion turbine is a critical area controlling the work output of the turbine and depends not only on the shape of the vanes but also on the angle at which each vane is set to a radial plane through the turbine axis. The vanes are normally mounted in inner and outer rings and it is essential, therefore, that the means on the vanes for locating them in the rings should be correctly located on them.

According to the present invention a repetition method of manufacturing a guide vane comprises the steps of first shaping the vane proper to its final configuration, supporting the vane in a jig which engages the vane proper at points or lines which in the final assembly of vanes define the theoretical throat area measured between adjacent vanes and machining the locating means on the vane while it is so supported. One such location may be at points or along a line at the trailing edge of the blade and another engagement is at a point or line on its convex face that would be nearest the trailing edge of the next vane when the two vanes are correctly assembled together. It is preferred that the vane should be located by its trailing edge and a single point on its convex face.

The present invention is particularly applicable when the vanes are formed as precision castings so that the vanes proper require no machining but it is also applicable when the vanes are formed as forgings to the final vane configuration or as forgings or castings and finished by machining. It will be seen that the present invention ensures that the locating means on the vanes shall be correctly machined with reference to a plane through the two lines that define the theoretical throat between the assembled vanes so that when the vanes are assembled, the correct throat area will be obtained.

A practical application of this invention will now be described, by way of example, with reference to the accompanying drawings whereof:

Figure 1 is a side view of a nozzle guide vane which is manufactured in accordance with the present invention.

Figure 2 is a view in the direction of arrow 2 of Figure 1.

Figure 3 is a diagrammatic development view showing the relative disposition of the vanes when mounted in position in the turbine.

2

Figure 4 is an end view of a jig for locating the vane of Figures 1 and 2 whilst it is being machined and also of a support for the jig,

Figures 5 and 6 are views of the jig as seen respectively in the direction of arrows 5 and 6 of Figure 4, and

Figure 7 is a part view of a milling machine with the jig of Figure 4 mounted thereon.

The present method is particularly applicable to the manufacture of vanes as shown in Figures 1 and 2 which comprise a vane portion proper—generally indicated at 10—and a pair of tablets 11 and 12. The vane is of aerofoil section (Figure 2) and is formed with a straight leading edge 13 and straight trailing edge 14. Each tablet 11 and 12 is a parallelogram in plan and has its front and rear edges 11a, 12a and 11b, 12b in line with one another whilst the front edges are parallel with the rear edges.

20 The guide vanes are mounted in the manner described in the specification to application No. 727,520, the tablets 11 and 12 being located in inner and outer rings so that part 10 lies generally radially of the rings and between them. 25 When so mounted, a development view showing the parts 10 of adjacent vanes in section is as in Figure 3.

The throat area of the guide vanes is determined by the distance x between the trailing edge 14 of each vane and the nearest point 15 to the trailing edge on the convex side 16 of the next adjacent vane. This area decides the work output of the turbine so that the distance x requires to be accurate—this, in turn, will be determined by the degree of accuracy with which the tablets 11 and 12 are mounted in the rings referred to. Finally, the method of machining the faces of the tablets which locate them in position in the rings will decide the distance x . This invention is directed to machining the tablets whilst the vanes are located by those parts of it which define the distance x —and hence the throat area. The parts are the trailing edge 14 and the point 15 at a certain determined position along the length of the vane (Figure 1).

To effect the location referred to the vane is mounted for machining in the jig of Figures 4 to 6. Turning to these figures: the jig comprises a block 17 formed with an opening 18 to accommodate the vane with its tablets 11 and 12 projecting from the opening. A V-shaped groove 19 is formed at the bottom of opening 18 and trailing edge 14 of the vane is received in this groove so that the blade is free to pivot about

this edge. A pin 20 with a rounded head is mounted part-way up one side of opening 18. The pin forms an abutment against which the convex face 16 of the vane is held by a screw 21. The screw 21 engages the vane by a cap 22 freely rotatable on the screw.

The points of engagement of pin 20 and cap 22 chordwise of the vane are determined by their location above groove 19. To determine their engagement lengthwise of the vane, the block carries at each side a stop 23 which is adjusted to engage the inner faces of the tablets 11 and 12 and positively locate the vane lengthwise of the jig. It is arranged that pin 20 engages face 16 at point 15.

The axes of pin 20 and cap 22 are relatively displaced in a manner which causes the edge 14 to bear against one side of groove 19 when screw 21 is tightened.

A pair of jaws 24 are carried on one side of opening 18 so that they overlie the leading edge 13 of the vane and are adjustable by nuts 25 to engage the edge and clamp the vane against groove 19 within opening 18. The surfaces of the block 17 shown in the drawing make the same angles to one another as the edges of tablet 11.

When a vane, with part 19 in its finished state, is mounted in the jig the top and bottom surfaces 26, 27 respectively are parallel to the front and rear edges 11a, 11b of tablet 11 (Figure 4): these surfaces are, therefore, also parallel to the front and rear edges 12a, 12b of tablet 12. Furthermore, the side edges of tablet 11 are parallel to surfaces 28 of block 17 but, of course, not to the corresponding side edges of tablet 12.

The jig is carried by a base 29 which is, in turn, mounted on the table 30 of, say a horizontal milling machine 31 (Figure 7). When the table 30 moves past the cutter 32, edge 11a of tablet 11 is machined. The jig is mounted in base 29 with surfaces 26, 27 horizontal so that the machined edge 11a will be horizontal.

It is preferred to have a pair of spaced cutters 32 simultaneously to machine edges 11a and 12a of tablets 11 and 12.

When so machined the jig is remounted on base 29 with edges 11b and 12b uppermost and these are similarly machined. When the jig is laid with its side surfaces on base 29 the side edges of tablet 11 may be similarly machined. Thus, the vane is located in the jig by edge 14 and point 15 and then has one tablet (11) completely machined and the front and rear edges of the other tablet (12) machined without removal of the vane from the jig.

The vane is then mounted in a similarly constructed jig so arranged, however, that the side edges of tablet 12 are parallel with the side surfaces 28 of block 17—these edges are then machined.

As shown in Figure 4, the base 29 is arranged to accommodate, at the same time, two jigs. In this way the edges of 11a, 12a of one vane may be machined simultaneously with edges 11b, 12b of another vane, the vanes being mounted side by side in the pair of jigs.

We claim:

1. For use in the manufacture of guide vanes for axial-flow turbines and compressors in which the vanes have end tablets for locating the vanes in rings with the trailing edge of a vane forming a throat area with the nearest point on the convex side of an adjacent vane, the herein described method of machining the edges of the tablets which consists in pivotally mounting the vane on its trailing edge and clamping the vane at said nearest point on the convex side and at a point approximately opposite said nearest point on the concave side, and moving the vane past a cutter with an edge of a tablet in a position to be machined.
2. A repetition method of manufacturing a guide vane having integral locating means, which method comprises the steps of shaping the vane proper to its final configuration, supporting the guide vane by engaging the vane proper at the trailing edge and at a location on its convex face that would be opposite the trailing edge of an adjacent vane when the two vanes are correctly assembled together, and machining the locating means on the vane while it is so supported.
